UNITED STATES PATENT OFFICE.

E. P. RUSSELL, OF MANLIUS, NEW YORK.

IMPROVEMENT IN FINGERS FOR HARVESTERS.

Specification forming part of Letters Patent No. 31,745, dated March 19, 1861.

To all whom it may concern:

Be it known that I, E. P. RUSSELL, of Manlius, in the county of Onondaga, in the State of New York, have invented a new and useful Improvement in Guard-Fingers for Harvesters; and I do hereby declare that the following is a full and exact description thereof, reference being had to the accompanying drawings, and to the letters of reference marked thereon.

In the drawings similar letters refer to like parts.

Figure 1 is a side elevation. Fig. 2 is a longitudinal vertical section. Fig. 3 is a plan view.

To enable those skilled in the art to make and use my invention, I will describe its construction and operation.

The finger A is made of cast-iron, of a general form similar to that of other fingers.

The cap B of the fingers is made of a separate piece of metal, and has a tenon or toe, a, which fits into a corresponding mortise or opening in the finger; C, the steel face-plate. This plate also has a toe or tenon, b, similar to that of the cap B.

c is the bolt or rivet which passes through cap B and plate C and secures them to the finger A.

It will be seen that that part of the finger upon which the face-plate rests is slightly concave.

The several parts being constructed as above, I first take the steel plate C, which is a thin plane plate, and lay it upon the curved surface

of the finger, at the same time inserting its toe or tenon b in the mortise in the projection at the front end of the finger. I then in like manner place the cap B upon the plate C and insert its toe or tenon a in the same mortise. I then drive up tightly or rivet the screw-bolt c, which causes the cap B to press the plate C forcibly down upon the curved surface of the finger. This pressure upon the plate C must be sufficient to throw it out of plane and make it coincide with the concavity of the contiguous surface of the finger. By this means the steel face-plate is well and easily secured to the finger without any fastening at its rear end excepting the square slot, and by reason of the concavity of this plate I secure a better shear cut.

I do not claim securing the steel cutter-plate C in the front end of the finger by means of the mortise or cavity in which a tenon on the front end of the face-plate is inserted.

Having thus fully described the construction and operation of my invention, what I claim as new, and desire to secure by Letters Patent, is—

The combination of the elastic steel face-plate C with the concave face of the finger A by means of the cap B and the single bolt or screw c, whereby said plate is drawn down upon the finger in the manner described, for the purposes set forth.

E. P. RUSSELL.
